Primary Examiner — Amber R Stiles*Assistant Examiner* — Earl B Elowsky(74) *Attorney, Agent, or Firm* — Craig R. Miles; CR MILES P.C.**CLAIM**

The ornamental design for a hose coupler retainer, as shown and described.

DESCRIPTION

FIG. 1 is a first perspective view of a hose coupler retainer, embodying my new design, shown in an environment of use; FIG. 2 is a second perspective view thereof, shown with the environmental subject matter removed for clarity of disclosure;

FIG. 3 is a first end elevation view thereof;

FIG. 4 is a second end elevation view thereof;

FIG. 5 is a first side elevation view thereof;

FIG. 6 is a second side elevation view thereof;

FIG. 7 is a bottom plan view thereof; and,

FIG. 8 is a top plan view thereof.

The broken lines are included for the purpose of illustrating portions of the hose coupler retainer that form no part of the claimed design. The additional broken lines shown in FIG. 1 depict environmental subject matter only and form no part of the claimed design.
